BOTTLE CARRIERS WITH REINFORCED BASE

Filed Feb. 2, 1962

INVENTOR.
GEORGE V. WOODLING

BY
Woodling, Kist, Granger + Ruit
Attnys.

base-pad wall means comprises a pair of pads 65 and 66 respectively connected to the left-hand end of the half-base portions 27 and 28 and the second base pad wall means comprises a pair of pads 67 and 68 respectively connected to the right-hand end of the half-base portions 27 and 28 (see FIGURE 2). These first and second base-pad wall means foldably overlap in face contacting relationship with the underneath side of the base wall means and are secured thereto to provide a double thickness. Throughout the entire assembly all of the face contacting surfaces may be secured together by suitable glue or other adhesive.

FIGURE 9 is a view the same as FIGURE 4, except that the internal surface of the surrounding wall means 21, 22, 23, 24, 25 and 26 and of the base-wall means 27 and 28, and the exposed external surface of the base-pad wall means 65, 66 and 67, 68 which comprise one continuous surface has metal foil means 69 secured thereto. The metal foil protects the sheet board, which is usually paper, from being soaked and damaged.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A carrier for bottles and other similar articles, said carrier being foldable from a collapsed condition to an erected condition, said carrier comprising centrally disposed handle means, wall means defining a box compartment with four corners, said wall means having opposed side-wall means each having end corner edges and opposed end-wall means each having end corner edges, said end corner edges of said side-wall means and of said end wall means being joined together to define said four corners, said opposed side-wall means having bottom edges, base-wall means having outer edges respectively connected to the bottom edges of said opposed side-wall means, said end-wall means comprising first and second pair of end panels, said first pair of end panels having inner adjacent edges and having a first pair of infold reinforcing flaps respectively connected along vertical fold lines to the inner adjacent edges thereof, said first pair of infold reinforcing flaps extending inwardly of the box compartment in face-contacting relation and being fixedly secured together to join the inner adjacent edges of the first pair of end panels, said first pair of infold reinforcing flaps constituting first end-wall rib means, said second pair of end panels having inner adjacent edges and having a second pair of infold reinforcing flaps respectively connected along vertical fold lines to the inner adjacent edges thereof, said second pair of infold reinforcing flaps extending inwardly of the box compartment in face-contacting relation and being fixedly secured together to join the inner adjacent edges of the second pair of end panels, said second pair of infold reinforcing flaps constituting second end-wall rib means, said first and second end-wall ribs means respectively having first and second riser portions extending respectively above the first and second pair of end panels, said handle means extending lengthwise of said carrier and having first and second load-carrying end-connection portions respectively secured to said first and second riser portions and constituting first and second load-carrying connections between said handle means and said first and second pair of end panels, said base-wall means having first and second end edges and base-wall rib means extending lengthwise thereof from one end edge to the other and projecting upwardly towards said handle means, said base-wall rib means having first and second load-carrying end connection portions, said first and second end-wall rib means having respectively first and second load-carrying bottom

connection portions, said base-wall means in the erected condition of said carrier being disposed at a first position substantially longitudinally co-extensive with said handle means and in the collapsed condition of the carrier being disposed at a second position longitudinally off-set with respect to said first position for a distance substantially equal to one-half the width of a pair of end panels, said first and second load-carrying end connection portions of said base-wall rib means and said first and second load-carrying bottom connection portions of said end-wall rib means being disposed respectively alongside each other in face-contacting relationship for securement with each other in the erected condition of said carrier, and load-carrying securement means securing said first and second load-carrying end connection portions of said base-wall rib means respectively to said first and second load-carrying bottom connection portions of said end-wall rib means, said handle means, said base-wall rib means and said end-wall rib means in the erected condition of said carrier lying substantially in the same plane and separating said box compartment into two half-compartments.

2. A carrier as defined in claim 1, wherein said load-carrying securement means is separable.

3. A carrier for bottles and other similar articles, said carrier being foldable from a collapsed condition to an erected condition, said carrier comprising centrally disposed handle means, wall means defining a box compartment with four corners, said wall means having opposed side-wall means each having end corner edges and opposed end-wall means each having end corner edges, said end corner edges of said side-wall means and of said end-wall means being joined together to define said four corners, said opposed side-wall means having bottom edges, base-wall means having outer edges respectively connected to the bottom edges of said opposed side-wall means, said end-wall means comprising first and second pair of end panels, said first pair of end panels having inner adjacent edges and having a first pair of infold reinforcing flaps respectively connected along vertical fold lines to the inner adjacent edges thereof, said first pair of infold reinforcing flaps extending inwardly of the box compartment in face-contacting relation and being fixedly secured together to join the inner adjacent edges of the first pair of end panels, said first pair of infold reinforcing flaps constituting first end-wall rib means, said second pair of end panels having inner adjacent edges and having a second pair of infold reinforcing flaps respectively connected along vertical fold lines to the inner adjacent edges thereof, said second pair of infold reinforcing flaps extending inwardly of the box compartment in face-contacting relation and being fixedly secured together to join the inner adjacent edges of the second pair of end panels, said second pair of infold reinforcing flaps constituting second end-wall rib means, said first and second end-wall rib means respectively having first and second riser portions extending respectively above the first and second pair of end panels, said handle means extending lengthwise of said carrier and having first and second load-carrying end-connection portions respectively secured to said first and second riser portions and constituting first and second load-carrying connections between said handle means and said first and second pair of end panels, said base-wall means having first and second end edges and base-wall rib means extending lengthwise thereof from one end edge to the other and projecting upwardly towards said handle means, said base-wall rib means having first and second load-carrying end connection portions, said first pair of end panels having a first load-carrying bottom connection portion between said first end-wall rib means and an end corner edge thereof, said second pair of end panels having a second load-carrying bottom connection portion between said second end-wall rib means and an end corner edge thereof, said base-wall means in the erected condition of said carrier

being disposed at a first position substantially longitudinally co-extensive with said handle means and in the collapsed condition of the carrier being disposed at a second position longitudinally off-set with respect to said first position for a distance substantially equal to one-half the width of a pair of end panels, said first and second load-carrying end connection portions of said base-wall rib means and said first and second load-carrying bottom connection portions of said end panels disposed respectively adjacent to each other for securement with each other in the erected condition of said carrier, and load-carrying securement means securing said first and second load-carrying end-connection portions of said base-wall rib means respectively to said first and second load-carrying bottom connection portions of said end panels, said handle means, said base-wall rib means and said end-wall rib means in the erected condition of said carrier lying substantially in the same plane and separating said box compartment into two half-compartments.

4. A carrier as defined in claim 3, wherein said load-carrying securement means is separable.

5. A carrier for bottles and other similar articles, said carrier being foldable from a collapsed condition to an erected condition, said carrier comprising, centrally disposed handle means, wall means defining a box compartment with four corners, said wall means having opposed side-wall means each having end corner edges and opposed end-wall means each having end corner edges, said end corner edges of said side-wall means and of said end-wall means being joined together to define said four corners, said opposed side-wall means having bottom edges, base-wall means having outer edges respectively connected to the bottom edges of said opposed side-wall means, said end-wall means comprising first and second pair of end panels, said first pair of end panels having inner adjacent edges and having a first pair of infold reinforcing flaps respectively connected along vertical fold lines to the inner adjacent edges thereof, said first pair of infold reinforcing flaps extending inwardly of the box compartment in face-contacting relation and being fixedly secured together to join the inner adjacent edges of the first pair of end panels, said first pair of infold reinforcing flaps constituting first end-wall rib means, said second pair of end panels having inner adjacent edges and having a second pair of infold reinforcing flaps respectively connected along vertical fold lines to the inner adjacent edges thereof, said second pair of infold reinforcing flaps extending inwardly of the box compartment in face-contacting relation and being fixedly secured together to join the inner adjacent edges of the second pair of end panels, said second pair of infold reinforcing flaps constituting second end-wall rib means, said first and second end-wall rib means respectively having first and second riser portions extending respectively above the first and second pair of end panels, said handle means extending lengthwise of the carrier and having first and second load-carrying end connection portions respectively secured to said first and second riser portions and constituting first and second load-carrying connections between said handle means and

said first and second pair of end panels, said base-wall means having first and second load-carrying end-connection portions, said first pair of end panels having a first load-carrying bottom connection portion between said first end-wall rib means and an end corner edge thereof, said second pair of end panels having a second load-carrying bottom connection portion between said second end-wall rib means and an end corner edge thereof, said base-wall means in the erected condition of said carrier being disposed at a first position substantially longitudinally co-extensive with said handle means and in the collapsed condition of the carrier being disposed at a second position longitudinally off-set with respect to said first position for a distance substantially equal to one-half the width of a pair of end panels, said first and second end-wall rib means having respectively first and second terminating bottom rib edges, said base wall means having first and second end base edges, said first and second end base edges in the erected condition of the carrier respectively positioned adjacent said first and second pair of end panels and at a level below that of said first and second terminating bottom rib edges, said first and second load-carrying end-connection portions of said base-wall means and said first and second load-carrying bottom connection portions of said end panels respectively disposed for securement with each other in the erected condition of said carrier, first load-carrying securement means securing said first load-carrying end-connection portion of said base-wall means and said first load-carrying bottom connection portion of said first pair of end panels together with said first end base edge positioned adjacent said first pair of end panels and at a level below that of said first terminating bottom rib edge, said first load-carrying securement means positioned between said first end-wall rib means and an end corner edge of said first pair of end panels, and second load-carrying securement means securing said second load-carrying end connection portion of said base wall means and said second load-carrying bottom connection portion of said second pair of end panels together with said second end base edge positioned adjacent said second pair of end panels and at a level below that of said second terminating bottom rib edge, said second load-carrying securement means positioned between said second end-wall rib means and an end corner edge of said second pair of end panels, said handle means and said end-wall rib means in the erected condition of said carrier lying substantially in the same plane and separating said box compartment into two half-compartments.

6. A carrier as defined in claim 5, wherein said load-carrying securement means is separable.
